CIRCUIT BREAKER

Harold G. Baxter, Baldwin, N. Y., assignor to
Westinghouse Electric Corporation, East Pitts-
burgh, Pa., a corporation of Pennsylvania

Application August 21, 1947, Serial No. 769,915

11 Claims. (Cl. 200—116)

1

This invention relates to circuit breakers and more particularly, to circuit breakers that are tripped open automatically in response to over-load currents.

One object of the invention is to provide a circuit breaker embodying improved means for causing quick opening and closing of the breaker contacts.

Another object of the invention is to provide a circuit breaker embodying an improved operating mechanism including an operating handle extending through an opening in the breaker housing and an overcenter spring operable by the handle to open and close the breaker, which overcenter spring also provides pressure to seal the handle opening in the housing.

Another object of the invention is to provide a circuit breaker wherein an overcenter operating spring provides pressure to seal the handle opening in all positions of the handle.

Another object of the invention is to provide an improved circuit breaker construction that is simple, reliable in operation and relatively inexpensive to manufacture.

The novel features that are considered characteristic of the invention are set forth in particular in the appended claims. The invention itself, however, both as to structure and operation, together with additional objects and advantages thereof, will best be understood from the following description thereof when read in conjunction with the accompanying drawing.

In said drawing:

Figure 1 is an elevational sectional view taken on line I—I of Fig. 2 through a circuit breaker embodying the principles of the invention;

Fig. 2 is a sectional view taken on line II—II of Fig. 1 and looking in the direction of the arrows.

Referring to the drawing, the circuit breaker is encased in a housing comprising a base portion 11 of molded insulating material and a cover plate 13 also of insulating material. A stationary contact 15 is rigidly mounted on an upturned portion of a conductor 17 secured by means of a screw 19 to the base 11. The conductor extends through the end wall of the housing where it is provided with a terminal screw 21 for connecting the breaker in an electrical circuit.

A movable contact 23, which cooperates with the stationary contact 15 to open and close the circuit, is rigidly mounted on an ear 25 formed over at right angles from a switch arm 27. The switch arm 27 is pivotally mounted on a pivot

2

pin 29, the ends of which are supported respectively in an opening in a boss 31 (Fig. 2) formed integral with the base 11 and a corresponding opening in a boss 33 formed integral with the cover plate 13. Pivotedly mounted on a pivot pin 35 on the switch arm 27 is a latch 37 which is biased by means of a spring 39 into engagement with a pin 41 projecting from an operator 43. The operator 43 is biased by means of an overcenter operating compression spring 45 to a closed position (Fig. 1) in which, by means of the pin 41 and latch 37, it holds the switch arm 27 in closed contact position and supplies the contact pressure between the contacts 15 and 23.

15 The overcenter spring 45 is coiled about a spring guide 47 having one end bifurcated as at 49 to slide over a headed pin 51 projecting laterally from the upper end of the operator 43. The other end of the spring guide 47 is pivotally 20 mounted on a pivot pin 53 supported between a pair of spaced projections 55 molded integral with a sliding plate 57 of molded insulating material. The plate 57 is mounted for longitudinal sliding movement in a pair of opposing channels 59 formed by projections 61 one of which is molded integral with the base 11 and the other of which is molded integral with the cover plate 13. The slide 57 is provided with a handle 63 projecting outwardly through a slot 65 in the 25 housing whereby the slide may be manually moved to an "off" position and to an "on" position to manually open and close the breaker.

The overcenter spring 45 is compressed with an initial compression between a shoulder 67 on 33 the spring guide 47 and a washer 69 encircling the spring guide and bearing against the upper rounded end of the operator 43 and the head of the pin 51 (see Fig. 2).

In order to operate the circuit breaker to 35 manually open the contacts, the slide 57 is moved, by means of the handle 63, from the "on" position, in which it appears in Fig. 1, to the right as far as it will go. During this movement the line of action of the compression spring 45 45 moves overcenter past the pivot pin 29. As soon as this occurs, the spring 45 biases and quickly moves the operator 43 in a counterclockwise direction until it is arrested by striking a shoulder 71 on a stop 73 molded integral with the side 50 wall of the base portion of the housing. Due to the latch 37 which normally latches the switch arm 27 to the operator 43, the switch member will be moved with the operator to separate the contacts.

55 The circuit breaker may be manually closed

by moving the slide 57 in the reverse direction, that is, from the "off" to the "on" position during which movement the line of action of the overcenter spring 45 passes over to the left of the pin 29, whereupon the spring 45 acts to quickly move the operator 43, and through the latch 37, the switch arm 27 in a clockwise direction to close the contacts.

The circuit breaker is also arranged to be tripped open automatically in response to overload currents occurring in the circuit controlled by the breaker. To this end a bimetal trip element 78 is provided to operate the latch 37 and release the switch arm 27 from the operator 43. The bimetal element 75 is secured by means of a mounting foot 77 to a conductor 79 which is secured to the base 11 of the housing by means of screws 81. The conductor 79 extends to the left (Fig. 1) through an opening in the end wall of the housing where it is provided with a terminal screw 83 for the purpose of connecting the breaker in an electrical circuit. The bimetal element 75 extends perpendicularly away from the base and is then bent at a right angle and its free end extends to the left beneath a tail 76 of the latch 37. The free end of the bimetal is electrically connected by means of a flexible conductor 85 to a projection 87 of the switch arm 27. The high expansion side of the bimetal element is on the left and lower side so that, when heated a predetermined amount in response to overload currents, it will deflect in a direction away from the base and engage and operate the latch 37 to release the switch arm 27. When this occurs, the switch arm 27 is immediately moved to the open position by means of a spring 89 which is coiled about the pivot pin 29 and has one end hooked over the edge of the operator 43 and the other end hooked over the edge of the switch arm, the spring 89 being tensioned in a direction to bias the switch arm 27 toward the open position. The opening movement of the switch arm 27 is limited by striking a shoulder 91 on the previously described stop 73. The tail 76 of the latch 37 is of sufficient length that it remains in contact with the pin 41 when the switch arm is in the open position.

A stop 93 moulded integral with the side wall of the housing is provided to prevent more than a slight amount of clockwise movement of the operator 43 when the switch arm 27 is unlatched therefrom. The operator 43 is normally restrained in the position shown in Fig. 1 by the engagement of the contacts, acting through the switch arm 27, the pin 41 and latch 37.

Before the contacts can be closed after the breaker has been automatically tripped open, it is necessary to move the operator to the open position to reconnect the switch arm thereto. This is accomplished by moving the slide 57 to the "off" position which effects movement of the operator 43 to the "off" position in the manner described in connection with the manual opening of the breaker. When the operator 43 is moved to the "off" position, the spring 39 re-engages the latch 37 with the pin 41 and thereafter the switch arm may be moved to the closed position in the previously described manner.

Since the handle 63 and the slide 57 are not displaced from the "on" position during an automatic opening operation, means is provided to visually indicate that the circuit breaker has been automatically tripped open. An indicator comprising a rod 95 slidably mounted in an opening in a boss 97 molded integral with the cover plate

13 and an opening in a rib 99 also molded integral with the cover plate is normally restrained against outward movement by the engagement of a projection 101 of the switch member 27 with a head 103 on the inner end of the rod 95 when the switch member 27 is in the closed position. The indicator 95 is biased outwardly by means of a spring 100. The spring 100 is coiled about the rod 95 and is compressed between the rib 99 and a washer 105 bearing against a pin 107 extending through an opening in the rod.

Upon movement of the switch arm 27 to the open position the projection 101 releases the rod 95 permitting the spring 100 to move the indicator outwardly when the outer end thereof projects outwardly beyond the housing to indicate that the contacts of the breaker are in the open position. When the switch arm is moved to the closed position, the projection 101 engages the head 103 and moves the rod 95 inwardly so that the outer end thereof lies approximately flush with the housing.

The operating spring 45, in addition to operating the breaker mechanism to open and close the contacts with a snap action and applying contact pressure in the closed position, also at all times presses the slide 57 upwardly and tightly against the housing to effectively seal the handle opening 65 in the housing. This seal prevents hot ionized gases or flame generated by the interruption of heavy short circuits from escaping around the handle. This protects the hand of the operator from being burned and insures that any inflammable material nearby will not be set on fire.

The breaker is trip-free of the operator in all positions of the handle, that is, the switch arm 27 may be automatically released from the operator and moved to the open position even though the handle is held in the closed position during the occurrence of an overload current.

Having described the invention in accordance with the patent statutes, it is to be understood that various changes and modifications may be made in the structural details thereof without departing from some of the essential features of the invention.

I claim as my invention:

1. A circuit breaker comprising a housing having an opening therein for receiving a handle, an operating handle disposed in said opening, a switch member movable to open and close said circuit, an operating lever for moving said switch member, a slidable member movable by said handle and closing said opening, and an overcenter compression spring operable upon movement of the handle to actuate said operating lever, said overcenter compression spring applying pressure to said slide to seal said handle opening.

2. A circuit breaker comprising a housing having an opening therein for receiving a handle, an operating handle disposed in said opening, a switch member movable to open and close said circuit, an operating lever for moving said switch member, a slidable member movable by said handle, and an overcenter spring operable upon movement of the handle to actuate said operating lever to open and closed position with a snap action, said overcenter spring at all times applying pressure to said slide to hold it in engagement with the housing and seal said handle opening.

3. A circuit breaker comprising a housing having an opening therein for receiving a handle, an

operating handle disposed in said opening, a switch member carrying a contact movable to make and break engagement with another contact, an operating lever for moving said switch member, a slideable member movable by said handle and closing said opening, and an over-center spring operable upon movement of the handle to actuate said operating lever, said over-center spring applying force to said operating member in one direction and biasing said contacts together when in closed position and also applying a force to said slide in the opposite direction to seal the slide against said handle opening in all positions of said handle.

4. In a circuit breaker, comprising a housing, the combination of a switch member movable to open and closed positions, operating mechanism for said switch member comprising an operating lever, a manually operable slide inside the housing having a handle extending through an opening in said housing, a spring operatively relating said operating lever and said slide, said spring being operable to move said operating lever to open and closed positions to operate said switch member to open and closed position, and said spring also applying pressure to said slide and holding it tightly against the inside of the housing and thereby closing the opening in said housing.

5. A circuit breaker comprising a housing having an opening therein for receiving an operating handle, an operating handle disposed for movement in said opening, a pivoted switch member movable to an open and to a closed position, an operating lever pivoted coaxially with said switch member and operable to move said switch member, latch means releasably coupling said switch member to said operating lever, a slide mounted for reciprocal movement by said handle and closing said opening, a compression spring operable by said slide to actuate said operating lever, said spring being disposed at all times to apply pressure between said slide and said housing to seal said opening, and a trip device operable in response to overload currents to operate said latch to permit movement of said switch member to open position even though said slide is held in closed position during the occurrence of an overload current.

6. A circuit breaker comprising a housing provided with an opening to receive an operating handle, an operating handle extending through said opening, a switch member movable to open and closed position, an operating lever for moving said switch member, a slideable member movable by said handle between an open and a closed position, means on said housing defining opposed channels in which said slide is movable to said open and closed positions, a compression spring operable by said slide for actuating said operating lever and for at all times providing pressure between said slide and said housing to seal said handle opening.

7. A circuit breaker comprising a housing having an opening therein, a switch member movable to an open position and to a closed position, an operating lever for moving said switch member, a slide disposed adjacent said housing and movable to an open position and to a closed position, a handle extending through said opening for operating said slide, and spring means op-

eratively relating said operating lever and said slide and operable by said slide to actuate said operating lever, said spring at all times applying a pressure between said slide and said housing to seal said opening.

8. A circuit breaker comprising a housing having an opening therein, a switch member movable to open and closed positions to open and close said circuit, an operating lever for moving said switch member, a slide disposed adjacent said housing for at all times closing said opening, an operating handle secured to said slide and extending through said opening for operating said slide, and spring means operable by said slide to actuate said operating lever to manually open and close said circuit, said spring at all times applying a pressure to said slide to seal said opening.

9. A circuit breaker comprising a housing having an opening therein for receiving a handle, a switch member movable to open and close said circuit, a slideable member having a handle portion extending through said opening and a closing portion for closing said opening, an over-center compression spring operable upon movement of said handle portion to actuate said switch member, and said overcenter compression spring applying pressure to said slideable member to cause said closing portion to seal said handle opening.

10. A circuit breaker comprising a housing having an opening therein for receiving a handle, switch means movable to open and close said circuit, a slideable member having a handle portion extending through said opening and a closing portion for closing said opening, an overcenter compression spring operable upon movement of said slideable member to actuate said switch means, said overcenter compression spring applying pressure to said slideable member to cause said closing portion to seal said handle opening, and trip means for effecting automatic opening movement of said switch means in response to overload currents.

11. A circuit breaker comprising a housing having an opening therein for receiving a handle, switch means movable to open and close said circuit, a slideable member having a handle portion disposed in said opening and a closing portion for closing said opening, an overcenter compression spring operable upon movement of said slideable member to actuate said switch means, said overcenter compression spring applying pressure to said slideable member to cause said closing portion to seal said handle opening, and trip means operable in response to overload currents to effect automatic opening movement of said switch means irrespective of the closed position of said slideable member.
